UNITED STATES PATENT OFFICE.

CARL SEVERIN, OF CHICAGO, ILLINOIS.

CHAIR.

1,189,178.

Specification of Letters Patent. Patented June 27, 1916.

Application filed March 1, 1915. Serial No. 11,300.

To all whom it may concern:

Be it known that I, CARL SEVERIN, a subject of the King of Sweden, residing at Chicago, in the county of Cook and State of Illinois, have invented certain new and useful Improvements in Chairs; and I do hereby declare the following to be a full, clear, and exact description of the invention, such as will enable others skilled in the art to which it appertains to make and use the same.

This invention relates to chairs, and has for its principal object to provide a chair particularly adapted for use in theaters, 15 halls and similar places wherein the chairs are arranged in rows and of such construction as to permit the occupant of the chair to move rearwardly without rising so as to increase the space between the rows of seats 20 and permit a person to readily pass by.

Another object is to provide a chair in which the seat is normally retained in forwardly extended position by gravity.

With these and other objects in view, the 25 invention consists in the novel construction, arrangement and formation of parts as will be hereinafter specifically described, claimed and illustrated in the accompanying drawing, in which:

30 Figure 1 represents a vertical sectional view through a theater seat constructed in accordance with the invention. Fig. 2 represents a vertical sectional view on the line 2—2 of Fig. 1. Fig. 3 represents a sectional view on the line 3—3 of Fig. 1, and Fig. 4 represents a fragmental perspective view of a part of the chair seat removed.

Referring to the drawing in detail, wherein similar reference numerals designate corresponding parts throughout the several views, the numerals 5 indicate the supports or legs of the chair, which, as usual, are arranged in pairs, the legs of each pair being connected by the side rails 6. A plurality of horizontally disposed bolts 7 are positioned through a row of horizontally aligned apertures 8 formed in each side rail 6 and each bolt is formed with a pair of spaced heads or flanges 9 disposed inwardly of the side rails 6 of each chair. Rollers 10 are rotatably mounted upon the plain portions of the bolts 7 intermediate the heads 9 and are formed with centrally disposed circumferential grooves 11. Guard strips 12 are secured upon the bolts 7 in-

termediate the inner heads 9 and the rollers 10 adjacent the forward portions of the side rail 6 and are formed with outwardly directed flanges 13 upon their upper edges disposed over the rollers 10.

60 The chair seat 14 and back 15 are rigidly connected and provided with suitable cushions 16.

U-shaped bearing members 17 having the parallel portions elongated and disposed in horizontal planes are engaged in the circumferential grooves 11 in the rollers 10 carried by the opposite side rails 6 of the relatively stationary parts of the chair. The web portions 18 of the U-shaped bearing 70 members are disposed rearwardly and constitute stops adapted to engage the rear rollers 10 of the rows to limit the forward movement of the chair seat and back. The parallel portions of the U-shaped members are 75 connected at spaced intervals by U-shaped reinforcing straps 19. The rows of bolts 7 on the opposite side 6 thereof are inclined downwardly from their rear ends so that the chair seat 14 and back 15 will move by gravity to the normal position illustrated in Fig. 1 in full lines.

When the seat is occupied and a person or persons desired to pass in the narrow space between the rows, the occupant exerts rearward pressure upon the seat 14 and the back 15, thus moving the latter rearwardly and increasing the space between the occupant and the next row of seats, permitting the person to conveniently pass by.

90 What I claim is:

1. A theater chair comprising pairs of legs, side rails connecting the legs of each pair, said side rails provided with apertures therein, bolts secured within said apertures and provided with a head on one end thereof, rollers rotatably secured to said bolts, said rollers provided with a centrally disposed circumferential groove, U-shaped bearing members secured to the under side 100 of a chair and adapted to receive the rollers between the parallel portions thereof, and a plurality of guard strips secured to the bolts.

2. A theater chair comprising pairs of 105 legs, side rails connecting the legs of each pair, said side rails provided with apertures therein, bolts secured within said apertures and provided with a head on one end thereof, rollers rotatably secured or 110

said bolts, said rollers provided with a centrally disposed circumferential groove, U-shaped bearing members secured to the under side of a chair and adapted to receive the rollers between the parallel portions thereof, guard strips secured to said bolts intermediate the head of said roller, outwardly directed flanges formed on the upper

edges of said strips and disposed over the rollers.

In testimony whereof I affix my signature in presence of two witnesses.

CARL SEVERIN.
